(57) **CLAIM**

I claim the ornamental design for the framing square, as shown and described.

DESCRIPTION

FIG. 1 is a perspective view of a first embodiment of the framing square;

FIG. 2 is a front view thereof;

FIG. 3 is a rear view thereof;

FIG. 4 is a left side view thereof;

FIG. 5 is a right side view thereof;

FIG. 6 is a top view;

FIG. 7 is a bottom view thereof;

FIG. 8 is a perspective view of a second embodiment of the framing square;

FIG. 9 is a front view thereof;

FIG. 10 is a rear view thereof;

FIG. 11 is a left side view thereof;

FIG. 12 is a right side view thereof;

FIG. 13 is a top view; and,

FIG. 14 is a bottom view thereof.

The ornamental design which is claimed is shown in solid lines in the drawings. The broken lines shown in the drawings are for illustrative purposes only and form no part of the claimed design.
